CLAIM

The ornamental design for a cover for electronic communications device or the like, as shown and described.

DESCRIPTION

FIG. 1 is a front perspective view of a cover for electronic communications device or the like showing the claimed design in an environment of use;

FIG. 2 is a front perspective view thereof of the cover for electronic communications device or the like showing the claimed design without the environmental communications device shown in FIG. 1;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines immediately adjacent to the shaded surfaces represent the bounds of the claimed design. All other broken lines depict environmental subject matter that forms

(Continued)

no part of the claimed design. The broken lines and unshaded regions bounded by broken lines form no part of the claimed design.

1 Claim, 7 Drawing Sheets

Related U.S. Application Data

a continuation of application No. 29/396,158, filed on Jun. 27, 2011, now Pat. No. Des. 656,495, which is a continuation of application No. 29/365,747, filed on Jul. 14, 2010, now Pat. No. Des. 642,169, which is a continuation of application No. 29/343,324, filed on Sep. 10, 2009, now Pat. No. Des. 622,716, which is a division of application No. 29/281,500, filed on Jun. 25, 2007, now Pat. No. Des. 606,751.
